UNITED STATES PATENT OFFICE

PERRY C. COLE, OF CLAY CENTER, KANSAS

ELEVATING GRADER

Application filed October 7, 1929. Serial No. 393,079.

My invention relates to elevating graders, the present invention being in the nature of an improvement of the grader described in my prior Patent No. 1,698,152, granted January 8, 1929.

The primary object of the invention is the provision of a grader for receiving loose soil from a windrow and for elevating this soil during the forward movement of the grader and for delivering it to a transverse conveyor from whence the soil may be deposited either on the ground at the side of the elevating grader or into wagons traveling at the side of the grader.

Another of my objects is the provision of a device of the character specified having simple means for driving the transverse conveyor.

One of the important objects of the invention is the provision of a transverse conveyor which is reversible so that the soil may be delivered at either side of the elevating grader.

Having in view these objects and others which will be pointed out in the following description, I will now refer to the drawings, in which—

Figure 1 is a view in side elevation of the elevating grader, certain portions being shown in section.

Figure 2 is a vertical sectional view through the elevating grader, the section being taken at right angles to the view in Figure 1.

Figure 3 is a view in perspective showing the shifting device for reversing the movement of the transverse conveyor.

Figure 4 is a plan view of a fragment of the mechanism for driving the transverse conveyor.

The frame of the elevating grader includes two pairs of vertical members 10 and 11 and two pairs of horizontal members 12 and 13. The members 10, 11, 12 and 13 are equal in length so that they form a perfect square. At each corner of the frame is a flanged pulley wheel or roller 14. The two squares are spaced apart as shown in Figure 2 and they are braced apart by means of braces 15. Each square is further provided with the

braces 16 and 17, the latter brace projecting forward to constitute a support. The braces 16 and 17 are both horizontal and the squares are further braced by means of the inclined braces 18 extending from the extremities of the brace 16 to an intermediate point in the brace 17.

The elevating drum includes two spaced apart flanged disks 19 having horizontal flanges, the disks being centrally apertured throughout the larger portion of their diameters. The horizontal flanged portion of each disk has secured thereto a track 20 for the flanged rollers 14. As shown in Figure 2, the horizontal flanges of the disk ride on the surface of the soil. The vertical portions of the two disks 19 are spaced apart as shown in Figure 2 and the space between the two disks is utilized for mounting the radial plates 21. These plates are secured to shafts 22 having bearings in the vertical portions of the disks 19. The opposite end portions of the shafts are bent as shown in Figure 2 into the direction of the plates 21 with the arms 23 projecting radially to within close proximity of the peripheries of the disks 19. Coil springs 24 connect the extremities of the arms 23 with the disks 19. These springs permit a limited pivotal movement of the arms 23 and consequently of the plates 21. Throughout substantially the first quadrant of the grader the peripheral opening to the space between the two disks 19 is closed by means of a curved plate 25. The curved plate is secured to the frame of the machine by means of braces such as those shown at 26 and 27. The forward end of the curved plate 25 is in close proximity with the surface of the soil but it is slightly above the point of contact of the horizontal portions of the disks 19 with the surface of the soil.

For conveying the soil into the path of the elevating grader I employ a scraper 28. This is preferably in the form of two scrapers which converge toward the rear and which tend to deposit the loose soil in the form of a windrow. The scraper 28 is secured to a lever 29 which is pivotally secured to a brace 30 on the frame. The pivotal connection between the lever 29 and the brace 30 is suffi-

ciently near the center or axis of the elevating grader so that the scraper is substantially concentric with the elevating grader regardless of its adjustment. The adjustments of the scraper may be made by means of any suitable device such as the chain 31, the free end of which is within convenient reach of the operator.

It will be apparent from the foregoing description that the soil which is deposited in the form of a windrow by means of the scrapers 28 will be immediately picked up by the elevating grader. This soil will be prevented by the curved plate 25 from falling out during the first part of its movement. During the second quadrant of the movement the soil will be carried upward and inward until the inclination of the plates 21 becomes such that the soil will slide off in an inward direction. Shields 32 are provided for preventing the soil from falling out prematurely and these shields terminate in slides 33 which constitute chutes for the soil as it leaves the elevating device. The soil entering the elevating grader will pass through smoothly unless it contains rocks or large stones. When such obstacles are encountered which are too large to pass readily through the elevating grader, the plates 21 will yield under the action of the springs so that the stones or rocks will be rolled by gravity until they are at the side of the elevating grader, after which the plates 21 resume their normal radial position until another obstacle is encountered.

The object of the elevating grader is to deposit the soil at one side or the other of the machine. For this purpose I have provided a transverse conveyor as best shown in Figure 2. This transverse conveyor includes a rigid frame having sprocket wheels 34 at its extremities. These two sprocket wheels 34 are designed for the purpose of driving an endless conveyor. Owing to the load which the transverse conveyor is compelled to carry, I insert a number of idlers 35 between the upper and lower ends of the conveyor. The frame of the transverse conveyor is mounted in slides 36 so that it may be shifted to deliver the soil at either side of the elevating grader. The slides 36 are provided with anti-friction devices as best shown in Figure 1.

The mechanism for driving the transverse conveyor includes a ring gear 37 secured to one of the disks 19. The shaft 38 has two pinions 39 which are adapted to engage the ring gear 37, the pinions 39 being so arranged that only one or the other of them may be in engagement with the ring gear 37 at one time. The shaft 38 drives a sprocket chain 40 which in turn drives the drive shaft 41 of the transverse conveyor, as shown in Figure 1 and as shown in greater detail in Figure 4. The shaft 38 has its bearings in arms 42 which are supported on the brace 30. As shown in Fig-

ure 3, the shaft 38 is square and the bearings in the arms 42 are round so that the shaft 38 has both turning and sliding movements with respect to the arms 42. In order to throw one or the other of the pinions 39 into gear with the ring gear 37 it is necessary that the shaft 38 be moved longitudinally. For this purpose the shaft 38 is provided with a grooved pulley 43 which is keyed or otherwise secured to the shaft. A lever 44 is pivotally secured to the brace 30 in a manner such that its free end rests in the groove of the pulley 43. The opposite end portion of the lever 44 is provided with an actuating member 45 which extends to within convenient reach from the operator's position. It is evident that the actuation of the rod 45 will cause one or the other of the pinions 39 to engage the ring gear 37 or the shaft 38 may be moved to neutral position so that neither pinion 39 would be in engagement with the ring gear 37. When one of the pinions 39 is in engagement with the ring gear 37 the shaft will be positively driven in one direction or the other and this movement will be transmitted through the chain 40 to the shaft 41 as shown in Figure 4. The shaft 41 is provided with a driven sprocket 46 and with a driving sprocket 47, the driving sprocket being in direct engagement with the sprocket chain of the transverse conveyor. Two idlers 48 are also provided for holding the sprocket chain of the transverse conveyor in intimate contact with the teeth of the sprocket wheel 47.

It is important that the transverse conveyor be so arranged that it may deliver the soil at either side of the elevating grader. The transverse conveyor is provided with a brace 49 extending from end to end of the transverse conveyor as best shown in Figure 2. This brace is provided with a plurality of apertures. The shaft 41 and the idlers 48 together with the frame to which they are secured are fixed so that they cannot partake of the sliding movement of the transverse conveyor. The two plates 50 are a part of this frame and they are both provided with apertured ears in direct contact with the brace 49. The apertures in the brace 49 are so spaced that two of the apertures may always be brought into registration with the apertures in the ears of the plates 50. In any position of adjustment of the transverse conveyor it is desirable that the transverse conveyor be prevented from sliding on its slideable connections. This is accomplished by inserting pins 51 through the registering apertures of the ears of the plates 50 and of the brace 49. In order to shift the transverse conveyor lengthwise it is only necessary to first remove the two pins 51, to move the shaft 38 into neutral position and then to slide the transverse conveyor into the desired position after which the pins 51 are

again inserted for holding the transverse conveyor in adjusted position.

In sliding the shaft 38 lengthwise it is necessary that the position of the sprocket chain 40 be not disturbed. This sprocket chain is driven through the sprocket wheel 52 which is connected with the shaft 38. The connection between the shaft 38 and the sprocket wheel 52 is such that the shaft is slidable in the sprocket wheel, as shown in Figure 3. In order to prevent the accidental shifting of the sprocket wheel 52 when shifting gears, I provide a fork 53 which embraces the sprocket wheel 52 and which is secured to the brace 30.

Having thus described my invention in such full, clear, and exact terms that its construction and operation will be readily understood by others skilled in the art to which it pertains, what I claim as new and desire to secure by Letters Patent of the United States is:

1. An elevating grader comprising a drum, a ring gear carried by said drum, a shaft having two spaced-apart pinions adapted to mesh with said ring gear at different times, a transverse conveyor slidably mounted in the upper portion of the drum, means operably connecting said shaft and said conveyor for driving the latter, and means carried by said shaft for moving said pinions selectively into and out of mesh with said ring gear.

2. An elevating grader including a drum to roll over the surface of the soil, means on said drum for picking up loose soil and for conveying the loose soil to the upper portion thereof, a transverse endless conveyor in the upper portion of said drum for receiving the loose soil from said drum and for delivering it at the side of said elevating grader, and means carried by said drum and said grader for driving said conveyor in either of two directions, said means including a ring gear carried by said drum, a shaft having two spaced apart pinions adapted to mesh with said ring gear at different times, means operatively connecting said shaft and said conveyor for driving the latter, and means carried by said shaft for moving said pinions selectively into and out of mesh with said ring gear.

In testimony whereof I affix my signature.
PERRY C. COLE.
